WOOD CUTTING DEVICE

Filed June 27, 1945

UNITED STATES PATENT OFFICE

2,423,807

WOODCUTTING DEVICE

Edward J. Zindrick, Chicago, Ill.

Application June 27, 1945, Serial No. 601,853

4 Claims. (Cl. 144—175)

1

This invention relates to a wood-cutting device and it is one object of the invention to provide a device of this character including a trough having improved means at one end for holding a blade so that by placing a strip or block of wood in the trough and imparting movement thereto longitudinally of the trough a strip of the desired thickness may be cut from the block or strip of wood.

A further object of the invention is to provide a wood-cutting device having a blade holder at one end of a trough so formed that it may be shifted vertically to adjusted position and thus dispose its blade in predetermined spaced relation to the bottom of the trough and thereby cause a strip cut by the blade to be of desired thickness.

Another object of the invention is to so form the blade holder that when it is applied to the end of the trough and securing screws tightened, it will be firmly braced against movement relative to the trough and a blade backed up and braced against movement outwardly of the trough when subjected to pressure as a block or strip of wood to be cut is forced against the sharp inner edge of the blade.

A further object of the invention is to provide a blade holder which may be formed as a single casting and thus cheaply manufactured. The invention, is illustrated in the accompanying drawings, wherein—

Figure 1 is a perspective view of one end portion of the trough.

Figure 2 is a perspective view of the blade holder and showing the blade carried thereby.

Figure 3 is a perspective view showing the blade holder applied to the trough.

Figure 4 is an end view illustrating the manner in which a strip is cut from a block or strip of wood.

Figure 5 is a perspective view of the upper portion of one arm of the blade holder.

Figure 6 is a perspective view of the blade.

The trough 1 constituting the body portion of the wood cutter may be of any length and width desired and has a bottom 2 and side walls 3 and 4, within the confines of which a block of wood 6 is placed for cutting. Recesses 7 are formed vertically in inner side faces of the walls 3 and 4 at the end of the trough and extend the full height of the side walls so that spaces 8 are provided at opposite sides of the end of the bottom 2 of the trough.

In order to mount a blade 9 at the end of the trough for cutting the block or strip 6 and forming a strip 6' of predetermined thickness, there

2

has been provided a blade holder 10 which is formed as a single casting and has side bars 11 extending upwardly from ends of a cross-bar or bridge 12. These side bars 11 are of such thickness that when they are engaged in the recesses 7 of the side walls 3 and 4 of the trough, inner surfaces of the side walls of the trough and the side bars will be flush with each other. Along their outer margins the bars 11 are formed with outstanding side flanges 12 for bearing against ends of the side walls of the trough, and these flanges are formed with vertically extending slots 13 through which are passed screws 14 carrying washers 15 for bearing against outer faces of the flanges at opposite sides of the slots 13 and applying clamping pressure to hold the blade holder in a vertically adjusted position when the screws are screwed into the threaded sockets or openings 16 of the side walls and tightened to a clamping position. When the screws are loosened, the blade holder may be shifted vertically from the position shown in Figure 3 to an adjusted position, such as shown in Figure 4, and the screws again tightened to secure the blade holder in the adjusted position. The blade will then be disposed a predetermined distance above the bottom 2 of the trough and when the block or strip 6 of wood is pushed longitudinally through the trough against the sharpened inner edge 17 of the blade, a strip of the desired thickness will be cut from this block or strip 6. The blade fits into slots 18 formed in the side bars 11 and since these slots correspond to the width of the blade and terminate in spaced relation to outer side edges of the bars 11, the dull edge of the blade will have abutting engagement with closed ends of the slots and ends of its sharpened edge will have abutting engagement with the side edge faces 19 of the recesses 7 and the blade thus prevented from becoming dislodged from the slots.

When this wood cutter is in use, it is placed upon a work bench with the end carrying the blade holder projecting slightly from an edge of the top of the work-bench. The blade holder is adjusted to dispose the blade a predetermined distance above the bottom of the trough, and a block of wood is then placed in the trough and shoved longitudinally of the trough to bring an end of the block or strip 6 into contact with the sharp, inner edge of the blade. The blade will thus be caused to cut through the block of wood, and since the block of wood rests upon the bottom of the trough, a strip of even thickness throughout its length will be cut from the block. It is thought that persons skilled in the art to

which the invention relates will be able to obtain a clear understanding of the invention after considering the description in connection with the drawings. Therefore, a more lengthy description is regarded as unnecessary.

Minor changes in the shape, size and arrangement of details coming within the field of invention claimed may be resorted to in actual practice, if desired.

Having thus described the invention, what is claimed is:

1. A wood cutter comprising a trough having a bottom and side walls, inner faces of said side walls being formed with vertically extending recesses at an end of the trough, a U-shaped blade holder having side arms and a bridge extending between lower ends of its side arms, the bridge being disposed under the bottom of said trough and the side arms being slidably received in the recesses of the side walls and formed with outstanding side flanges overlapping ends of the side walls, the side flanges being formed with vertically extending slots and the side flanges of the trough being formed with threaded sockets, screws passing through the slots of the blade holder and into the threaded sockets of the trough and carrying washers overlapping outer faces of the flanges at opposite sides of the slots for gripping the flanges and firmly securing the blade holder in a vertically adjusted position when the screws are tightened, the side arms of the blade holder being formed with slots extending horizontally from their inner side edges, and a blade extending between the side arms of the blade holder with its end portions engaged in the slots of the said arms and having a sharpened edge presented inwardly of the trough for cutting engagement with wood placed in the trough and thrust longitudinally toward the blade.

2. A wood cutter comprising a trough having a bottom and side walls, the side walls being formed with vertically extending recesses at an end of the trough, a U-shaped blade holder having side arms and a bridging bar between lower ends of its side arms, the bridging bar being disposed under the bottom of the trough and the side arms being slidably received in said recesses, means for clamping the side arms of the blade holder to the side walls of the trough and releasably securing the blade holder in a vertically adjusted position, the side arms of the blade holder

being formed with slots leading from their inner side edges, and a blade extending horizontally between the side arms of the blade holder with its end portions engaged in the slots thereof, and 5 said blade having a sharpened edge presented inwardly of the trough for cutting engagement with wood stock placed in the trough and shoved longitudinally toward the blade.

3. A wood cutter comprising a trough having a bottom and side walls, a blade holder including bars disposed vertically against ends of the side walls and shiftable vertically along the same to adjusted positions, means for securing the bars in vertically adjusted positions upon the side walls, said bars having slots leading from their inner side edges, and a blade extending between the bars with its ends engaged in the slots and its sharpened edge presented inwardly of the trough.

4. A wood cutter comprising a trough having side walls formed with vertically extending recesses in their side faces at one end of the trough, a blade holder having portions fitting into said recesses and formed with horizontal slots leading from their inner side edges and other portions abutting ends of the side walls and formed with vertical slots, a blade extending between the portions fitting in the recesses and having its ends engaged in the horizontal slots thereof, and fasteners passed through the vertical slots of the blade holder and screwed into threaded sockets formed in the side walls of the trough and, when tightened, applying clamping pressure to releasably secure the blade holder in a vertically adjusted position.
